UNITED STATES PATENT OFFICE.

SVANTE R. W. M. BAGER, OF SOUTH MILWAUKEE, AND MITCHELL L. FYKSE, OF MILWAUKEE, WISCONSIN, ASSIGNORS TO BUCYRUS COMPANY, OF SOUTH MILWAUKEE, WISCONSIN, A CORPORATION OF WISCONSIN.

PORTABLE ENGINE.

Application filed August 26, 1922. Serial No. 584,592.

To all whom it may concern:

Be it known that we, SVANTE R. W. M. BAGER and MITCHELL L. FYKSE, citizens of United States, and residents, respectively, of

5 South Milwaukee and Milwaukee, both in the county of Milwaukee and State of Wisconsin, have invented certain new and useful Improvements in Portable Engines; and we do hereby declare that the following is a

10 full, clear, and exact description thereof.

Our invention relates to new and useful improvements in portable engines, and has for its principal object to provide a smoke stack for such engines which can conveniently be lowered out of the way when passing under obstructions, such as bridges, trolley wires, and the like.

Our invention is equally adaptable to any sort of portable engine, whether operating

20 on land or in the water, and whether having a horizontal or vertical boiler thereon. We have particularly in mind that type of portable engine known as a revolving steam shovel, having a boom, dipper and dipper

25 handle. Such a portable engine as this is shown in our figures and described herein-after, but it should be understood that our invention is not limited to this particular type.

30 The boiler of a portable engine is usually provided at the top with smoke conveyor, the bottom part of which is of about the same diameter as the smoke box of the boiler, and the top of which is considerably smaller. Different parts of this are known to the trade by different names, but the entire device will be described herein as a "smoke conveyor."

Portable engines usually contain various 40 different power sources, such as engines for propelling, rotating, hoisting, thrusting, and the like, and it is our intention to utilize for our invention any or none of these power sources.

45 For a great many years portable engines have been built with the smoke conveyor hinged, so as to lower it before passing under overhead obstructions. It is obvious that the hinge should be placed as low as possible, so that the machine can pass under the lowest possible obstructions, and for this purpose alone.

Considerable trouble has always been met in lowering the smoke conveyors of portable

engines, due to the force with which they fall when lowered, resulting in denting or damaging either the smoke conveyor or the part of the machine against which it strikes.

It is our object to eliminate this trouble, and to provide a more convenient means for lowering the smoke conveyor than any hitherto in use.

In the particular exemplification shown and described herein, we use the hoisting engine, offset by the weight of the excavating dipper, thus rotating the rear end of the dipper handle, and pulling upon the hinged smoke-conveyor, by means of a chain connecting said handle to said smoke-conveyor.

Other advantages of the simple design of 70 our smoke conveyor, and its lowering and raising means, will naturally suggest themselves as the description progresses.

With these general objects in view, the invention resides in the novel features of 75 construction, combination and arrangement of parts which will be hereinafter more particularly described and claimed, and shown in the accompanying drawings, wherein:

Figure 1 is a side view of a portable engine of the steam shovel type, with the smoke conveyor partially lowered by means of our invention.

Figure 2 is a side view of the same machine, with the smoke conveyor in the same 85 position as in Figure 1, but with the strut in place as hereinafter described.

Figure 3 is a side view of the same machine, with the smoke conveyor entirely lowered by means of our invention.

Referring more particularly to the drawings, it will be seen that 1 represents a portable engine of the steam shovel type, carrying on its forward end a boom 2, on which is supported, for rotation and translation, a dipper handle 3, carrying a dipper 4. The portable engine 1 contains a steam boiler, the upper part of the smoke box 5 of which is shown. The smoke conveyor consists of a small cylindrical portion 6 and a truncated 100 conical portion 7. The smoke conveyor is fastened to the top of the smoke box 5, at the rear side thereof, by hinge 8. At the opposite side of the base of the smoke conveyor is a fastening 9, from which extends 105 a chain 10, to a proper fastening 11 on the dipper handle 3. The rotation of the dipper handle 3 is controlled by the hoist rope 12,

actuated by a hoist engine not shown. The translation of the dipper handle 3 is effected by racks 17 on the under side thereof, and by pinions 18 mounted on the boom 2, engaging said racks, and rotated by the thrusting engine 13.

There is provided a strut 14, hinged (preferably detachably) at 15, at the opposite edge of the top of the smoke box 5 from the hinge 8. The smoke conveyor in its normal position, is shown by broken lines in Figure 1.

The smoke conveyor could be broken in any other horizontal plane than that shown, and the hinge 8 appropriately applied, such as at 16. When not in use, the chain 10 can be detached at 9 and 11, and stored away.

To lower the smoke conveyor, the chain 10 is attached by its respective ends at 9 and 11, so positioning the dipper handle 3, by means of the hoist rope 12 and the boom engine 13, as to take the slack out of the chain 10. The smoke conveyor is pushed to the rear, until its center of gravity is rearward of the hinge 8, as shown in Figure 1. The smoke conveyor is then lowered, by taking in the hoist rope 12. The strut 14 is raised, about the hinge 15 as a pivot, until the chain 10 bears upon it, as shown in Figure 2. The hoist rope 12 is further taken in until the smoke conveyor is completely lowered, as shown in Figure 3. The strut and chain can then be removed and the boom lowered for passing beneath the obstruction. The object of the strut 14 is to provide the necessary direction of pull on the fastening 9, when the smoke conveyor is in its lowest position.

To raise the smoke conveyor the above mentioned operations are reversed, and the rope 12 is payed out, the motive power being furnished by the kinetic energy of the dipper, stored up by its previous hoisting.

From the foregoing description, taken in connection with the accompanying drawings, it will be obvious that many changes may be made in the form and proportions of the different parts of the invention and in the manner of assembling and disassembling the same, without departing from the principal features thereof as outlined in the appended claims.

We claim:

1. In a portable engine, the combination of a boiler; a smoke box above said boiler; a smoke conveyor; a hinge connecting said smoke-conveyor to one side of said smoke-box; power-actuated means for raising and lowering said smoke-conveyor about said hinge, said power-actuated means including a flexible member; and a pivoted strut for changing the direction of pull in said flexible member.
2. In a portable engine, having at least one prime-mover, the combination of a boiler; a smoke-box above said boiler; a smoke-conveyor above said smoke-box; a hinge

connecting said smoke-conveyor to one side of said smoke-box; a flexible connection between the other side of said smoke conveyor and one prime mover of said portable engine, and a pivoted strut, on the free end of which can rest said flexible connection; all for the purpose of raising and lowering said smoke conveyor about said hinge.

3. In a portable engine, the combination of a boiler; a smoke-box above said boiler; a smoke-conveyor above said smoke-box, hinged at one side of said smoke box; a boom pivoted at one end of said portable engine; a dipper handle mounted on said boom for rotation and translation; means for rotating and means for translating said handle; and a flexible connection between said smoke-conveyor and said handle, for the purpose of raising and lowering said smoke-conveyor.

4. In a portable engine, the combination of a boiler; a smoke-box above said boiler; a smoke-conveyor above said smoke-box, hinged at one side of said smoke-box; a boom pivoted at one end of said portable engine; a dipper handle mounted on said boom for rotation and translation; means for rotating and means for translating said handle; a flexible connection between said smoke-conveyor and said handle; and a pivoted strut, on the free end of which can rest said flexible connection; all for the purpose of raising and lowering said smoke-conveyor.

5. In a portable engine, having at least one prime-mover, the combination of a boiler; a smoke-box above said boiler; a smoke-conveyor above said smoke-box, hinged at one side of said smoke-box; a connection between the other side of said smoke-conveyor and one prime-mover of said portable engine; and a pivoted strut, on the free end of which can rest said connection; all for the purpose of raising and lowering said smoke-conveyor.

6. In a portable engine, the combination of a boiler; a smoke-box above said boiler; a smoke-conveyor above said smoke-box, hinged at one side of said smoke-box; a boom pivoted at one end of said portable engine; a dipper handle mounted on said boom for rotation and translation; means for rotating and means for translating said handle; and a connection between said smoke-conveyor and said handle, for the purpose of raising and lowering said smoke-conveyor.

7. In a portable engine, the combination of a boiler; a smoke-box above said boiler; a smoke-conveyor above said smoke-box, hinged at one side of said smoke-box; a boom pivoted at one end of said portable engine; a dipper handle mounted on said boom for rotation and translation; means for rotating and means for translating said

handle; a connection between said smoke-conveyor and said handle; and a pivoted strut, on the free end of which can rest said connection; all for the purpose of raising and lowering said smoke-conveyor.

8. In a portable engine, having at least one prime-mover, the combination of a boiler; a smoke-box above said boiler; a smoke-conveyor; a hinge connecting said smoke-conveyor to one side of said smoke-box; and means for utilizing said prime mover to raise and lower said smoke-conveyor about said hinge, said means including a flexible member, and a pivoted strut for changing the direction of pull in said flexible member.

9. A pivoted strut, associated with the means for raising and lowering the smoke-conveyor of a portable engine, and so disposed as to change the direction of application of the force which performs the raising and resists the lowering.

10. In a portable engine, the combination of a boiler; a smoke-box above said boiler; a smoke-conveyor pivotally connected to said smoke-box and adapted to swing through substantially 180° about its pivot; and power-actuated means for raising and lowering said smoke-conveyor.

SVANTE R. W. M. BAGER.
MITCHELL L. FYKSE.
